UNITED STATES PATENT OFFICE.

ALEXIUS T. LUNDQVIST, OF NEW YORK, N. Y.

PIN-TICKET.

SPECIFICATION forming part of Letters Patent No. 256,342, dated April 11, 1882.

Application filed February 13, 1882. (No model.)

To all whom it may concern:

Be it known that I, ALEXIUS T. LUNDQVIST, of New York, in the county of New York and State of New York, have invented certain new and useful Improvements in Pin-Tickets; and I do hereby declare that the following is a full, clear, and exact description of the invention, which will enable others skilled in the art to which it appertains to make and use the same, reference being had to the accompanying drawings, which form a part of this specification, and in which—

Figure 1 is a plan or top view of my improved pin-ticket. Fig. 2 is a perspective view of the reverse or back part of the same. Fig. 3 is a cross-section through the same. Fig. 4 is a similar view, showing it applied to a piece of cloth or other fabric; and Figs. 5 and 6 represent modifications in the construction of the ticket.

Similar letters of reference indicate corresponding parts in all the figures.

My invention has relation to so-called "pin-tickets" for marking dry-goods or other soft fabrics or articles of clothing with the price or quality of the goods, or such other marks or descriptive matter as it may be desirable to place upon them; and it consists in the improved construction of a tag or ticket of that class, as hereinafter more fully described and claimed.

My improved pin-ticket is composed of three parts—viz., a piece of paper, card-board, or other suitable material, A, upon which the marks are written or printed, a back plate or mount, B, made of brass or other suitable sheet metal, and a double-pronged pin, C, for the attachment of the tag or ticket to the goods to be marked. The mark-card A is secured upon plate B by turning down a flange, b, of the latter all around the edge of the card; or, instead of a solid or contiguous holding-flange, b, as shown in Fig. 1, the edge of the plate may be cut to form lips c c, as shown in Fig. 5, which, when turned down over the edge of the card, perform the same function as the solid flange b. Again, the card A may be, as in Fig. 1, of the same size as the plate B, upon which it is mounted; or it may be of the same width, but longer, so as to be extended at both ends of the plate, as shown in Fig. 5; or, again, it may be both longer and wider than the plate, as in Fig. 6, so as to overlap both the ends and sides of the latter. Where a card

larger than the plate is used pointed or round-ed lips c c are used to clamp the card upon the plate, instead of the continuous card-frame or flange b. The middle part of the plate B is pressed and cut in a suitably-constructed die to form two parallel hinge-loops, a a, leaving the body of the plate flat and smooth, so that the card A, or that part of it which covers the same, will lie perfectly flat and smooth on the plate.

C is the double-pronged fastening-pin, which is inserted through the loops a a, which form a hinge for the same.

No part of the pin, it will be seen, projects up over the flat inner surface of the plate, so that the card may be written upon or otherwise marked without the least inconvenience.

By making the double-pronged pin C hinged in the manner described, instead of attaching it rigidly to the plate B or to the card, the latter is enabled to adjust itself upon the goods on which it is affixed, so as to be in an easy and convenient position for writing on it. Another advantage is that the tickets may be packed by folding the pin down flat upon the back, so as to occupy but very little room; nor is there any danger of the card and its back plate becoming detached from the pin in handling the goods.

Having thus described my invention, I do not claim broadly a tag-holder consisting of a metallic base or base-plate having holding prongs or points for its attachment to the fabric to be marked; but

What I claim as my improvement, and desire to secure by Letters Patent of the United States, is—

The improved pin tag or ticket for marking goods herein shown and described, the same consisting of a marking-card, A, of suitable size and shape, a sheet-metal back plate, B, provided with suitable means for the attachment of the card and having the hinge-loops a a, and double-pronged hinged pin C, constructed and combined substantially as and for the purpose shown and set forth.

In testimony that I claim the foregoing as my own I have hereunto affixed my signature in presence of two witnesses.

ALEXIUS THEODOR LUNDQVIST.
